COUNTERBALANCED HINGE

William Rees Jones, East Rochester, N. Y., as
signor to Robert Trent Jones, Montclair, N. J.

Application July 18, 1950, Serial No. 174,448

1 Claim. (Cl. 16—141)

1

This invention relates to hinged structures and is particularly directed to devices for counterbalancing the weight of a movable hinged element.

In certain applications of hinged structures, particularly when the movable element or member is of substantial weight and is horizontally hinged, i. e., when the axis of the hinge pivot is horizontal, it is desirable to counterbalance the weight of the member in some manner. Typical applications of hinged structures which involve a horizontally disposed, vertically movable member are: hatch covers, trap doors and covers for various types of cabinets. Floor gratings or racks may also be hinged to vertical walls so that they may be moved up out of position when desired. In refrigerator cars, for example, floor racks or pallets are used to provide a raised platform upon which materials may be stored so as to permit adequate ventilation and the circulation of chilled air beneath the stored materials, or even provide space for ice or other refrigerating instrumentalities. When the racks are not in use and when it is desired to clean the flooring of refrigerator cars, the racks may be pivoted upward, it being then necessary, in cars heretofore used, that the outer ends of the racks be hooked to the vertical wall to prevent them from dropping down. The racks used in refrigerator cars are of heavy construction to support the weight of the articles carried on them, and are, therefore, of substantial weight so that if they are permitted to drop in a free fall, when unhooked from the walls, considerable damage may be done to them or to the insulated floor against which they strike. There is also a serious and constant danger or injury to personnel required to work in the car and to raise and lower these floor racks.

It will be appreciated that in most arrangements in which a movable member is horizontally hinged, it is desirable to prevent the rapid descent of the member from the vertical to the horizontal position, this problem being singularly acute in the case of floor racks in refrigerator cars. Therefore, it is an important object of this invention to provide a new and improved device which will retard the movement of the hinged movable member as the outer end moves downward into the horizontal position.

A further object is to provide a novel, simplified and rugged device which counterbalances the increasing moment of a horizontally hinged movable member of substantial weight as it is moved from the vertical position to the horizontal po-

2

sition, thereby facilitating the safe handling of said member.

An additional object of this invention is to provide a means which in addition to fulfilling the above objects will also provide means for retaining the movable member in the vertical and in the horizontal position without additional locking means.

To these and other ends, presently preferred embodiments of the new device include a spring-balanced hinge having a hinge member adapted for attachment to a movable door or rack, and a second hinge member which is adapted for attachment to a supporting structure. A hinge pintle or suitable connecting means is provided to connect the two hinge members. A cam surface is provided on the underside of the first hinge member and is adapted to bear against a yieldable cam-contacting member which is pressed against the cam surface. The cam surface is so shaped as to bear increasingly (e. g. with increasingly greater displacement) against the cam-contacting member as the first hinged member moves from the vertical position to the horizontal position, and in such manner the increasing moment of the movable element secured to the movable hinged member is counterbalanced by the increasing compression exerted by the cam-contacting member against the cam surface.

For a more detailed description of certain examples of the invention, reference is made to the drawings wherein:

Fig. 1 is a side view of one particularly effective form of the invention;

Fig. 2 is an end view of the form of the device of Fig. 1;

Fig. 3 is an exploded, fragmentary, perspective of certain parts of the device of Figs. 1 and 2; and

Fig. 4 is a side view of an alternative form of the invention.

Referring first to Figs. 1, 2 and 3, the hinge device consists of two hinged members or leaves, such as members 10 and 12. Hinged member 10 includes, a vertically disposed arm or plate 11 which is adapted to be secured to a wall or other vertical supporting structure 25, and a horizontal outwardly extending arm 24 which is substantially at right angles to the vertical arm 11. Suitable hinge connections 23 are provided at the outer end of arm 24, e. g. curved socket elements 23 integrally projecting from the arm portion 24, to constitute part of the hinge knuckle. The hinged leaf or plate 12 is also provided with suitable complementary hinge connections 26 which con-

stitute similar socket elements and which are adapted to interfit with the hinge connections 23 of the hinge member 10. Suitable pivoting hinge means, such as pintle 20, is carried in the knuckle formed by the socket elements, in the usual fashion to maintain the two leaves 10, 12, in hinged relationship and thus to provide an axis about which the hinge leaf or member 12 may be turned. If desired, when used for a refrigerator car, the hinge member 10 may also have a lower foot 25a to engage the floor 25b for proper spacing and better support and rigidity of the member 10.

In accordance with the present invention, a supplemental lever or arm 19, having a lower cam surface 18 as described below, is also pivotally carried on the pintle 20, by a hinge connection lug or socket element 27 formed integrally at one end of the lever 19, above the cam surface 18. As shown in Figs. 2 and 3, the pivoting lug 27 of the lever may fit between the socket elements 26 of the hinge leaf 12, the latter elements being disposed between the corresponding parts 23 of the leaf 19, and all being aligned on the pintle 20. The long, upper edge or face of the lever 19 is adapted to abut flatwise against the underside of the swinging hinge leaf 12; although an operative device may be provided wherein the lever remains a separate element (but pressed against the leaf 12 to the extent necessary, by the spring structure described below), the lever is preferably secured to the underside of the movable leaf or member 12 by welding or other suitable means. Alternatively the lever 19, or equivalent rugged means to provide the cam surface 18, may be initially formed as an integral part of the hinge member 12, for example by making a single forging which constitutes the two instrumentalities.

A bracket 13 is fixed to the vertical arm 11 of the hinge member 10 by secure means, such as the bolts 29 and nuts 28; while the bracket can alternatively be welded or otherwise joined or made integrally with the hinge member 10, and while the bolts 29, if used, can merely provide attachment between the member and bracket, they may conveniently serve the further function (as shown) of securing the hinge element 10 to the wall or other supporting structure 25. An upstanding cylindrical boss 15 is provided on the bracket 13, and has a hollow cylindrical core adapted to receive a heavy coil spring 14, which may be a single coil as shown, or of other sort, such as plural, coaxial coils for extra heavy duty. A telescoping cylindrical tube member 16 is slidably mounted on the exterior surface of the boss 15 and is provided at its upper end with a platform 17 which is adapted to abut the curved cam surface 18 of the lever or arm 19. The coil spring 14 supported on the bracket 13 and within the telescoping elements 15, 16, is maintained in compression so that it presses against the underside of the platform 17 and urges the latter upwardly toward the hinge axis (i. e. the pintle 20) into yieldable but firm pressure contact with the cam surface 18.

It will be understood that the movable hinge leaf 12 is suitably secured to the element 31, such as a floor rack, trap door or other structure, which is to be moved between a lowered position as shown and an upper or upright position as indicated by dotted lines in Fig. 1. In its lower position, the element 31 may have means (not shown) of conventional sort at its outer end, to arrest it and hold its supported weight at a de-

sired locality. In most cases, two or more such hinge structures are used for a given rack, door or the like, being spaced along a common axis at the back edge of the latter; but since the hinges may be all identical, illustration and description of the operation of a single one is believed sufficient, e. g. to indicate the manner in which a plurality of them will function in unison.

In operation, as the hinged element 31, which is attached to the hinge member 12, is swung down, e. g. from the dotted line position of Fig. 1, the cam surface 18 depresses the spring 14 to a greater and greater extent causing the spring to be increasingly compressed and to exert a progressively greater counterbalancing effect to offset the increasing force of gravity on the hinged element 31. The cam surface 18 is eccentrically disposed with respect to the axis of the hinge (or may be considered as lying in a spiral curve about that axis) so that when the member 12 is rotated in one direction about the axis, e. g. from the vertical to the horizontal position, the radius of the engaged part of the cam surface increases, causing the cam engaging member or platform 17 to be displaced forcibly and continuously in a downward direction or away from the axis 20.

When the hinged element 31 is in the upright position, indicated by the dotted line in Fig. 1, the top surface or platform 17 of the spring-pressed tube 16 engages the flat step 22 of the cam surface 18, thus biasing the hinged element against swinging downward. By providing a similar flat step at the other end of the cam surface 18, e. g. at the locality 22a, the hinged member may be similarly biased in a horizontal position when the hinged element has been moved somewhat past a selected center such as indicated by the dotted line 32. The biasing effect results from the spring-pressed surface rising slightly, or at least seating itself against the corresponding flat section of the cam surface 18. Although such biasing of the hinged element in its vertical and horizontal positions affords a means of retaining the hinged element in the position desired, the hinge element can be readily removed (as by a slight pull) from the respective spring-biased positions. It will be appreciated that by varying the shape of the arc of the cam surface and by increasing or decreasing the compressive force of the coil spring, the counterbalancing effect of the arrangement may be varied. It will also be understood that if desired, the special biasing effects described above may be dispensed with, or may be made more pronounced, as by curving the cam surface 18 inward toward the hinge axis at the desired localities for releasable arrest of the hinged structure.

In addition to counterbalancing the effect of gravity on the hinged element, the inter-action of the cam surface 18 of the lever or arm 19 with the top platform surface 17 of the spring-pressed tube 16 provides such effect in a positive manner, and may also, if desired, afford a final, positive check to the downward movement of the hinged element 31, i. e. by the platform 17 abutting a more remote portion of the underside of the lever or arm 19.

In Fig. 4 an alternate form of the spring-pressed means is shown, the hinge members 33 and 34 corresponding to hinge members 10 and 12 in Figs. 1, 2 and 3, and the lever or arm 35 corresponding to the lever 19 in the preceding figures. In the embodiment shown in Fig. 4,

the means which yieldingly press against the cam surface 36 of the lever or arm 35 comprises a resilient leaf spring or strip 39, which is suitably fixed to the hinged member 33 by means such as nuts and bolts 37 and 38.

Although in both of the devices shown the respective cam arms 19 and 35 are preferably attached to or integral with the movable hinge members respectively, the cam arm or lever may, in some cases (as explained above) be separate and merely carried by its pivotal bearing surface (in the lug 27 or 40) on the hinge pin 20 or 41. Although such arrangements may be less serviceable and may require omission of a biasing surface portion of the cam surface for the horizontal position, the pressure of the spring assembly will ordinarily keep the cam arm in operative position against the swinging part or parts.

Although for some purposes, the spring-pressed platform or other cam engaging member can be embodied in other ways, as for example, by locating a telescoping, platform-supporting guide inside instead of outside the spring 14, the illustrated structures are singularly effective and satisfactory, the arrangement of Figs. 1 and 2 providing an especially rugged hinge that is adapted for very heavy duty. The platform 17 is firmly seated at all times and the spring securely held in proper alignment, yet both the spring and the tube 16 are amply free to move up and down as the hinged floor or other element is rocked about the hinge axis.

As indicated above, one structural combination in which the apparatus of this invention is extraordinarily useful is in railroad refrigerator cars, the present devices (especially in Figs. 1 and 2) providing means for hinged supporting, from the vertical walls, the heavy racks or pallets upon which products are carried above the insulated flooring of the car. My improved hinge structures are particularly effective in counterbalancing the weight of the racks, so that when the car is empty, the racks can be very easily raised and lowered to permit cleaning beneath them, with no danger of a rack falling in such way as to damage itself or the underfloor, or to injure the operator. Indeed, with the danger of structural shock thus minimized, the racks may be of lighter construction than is now employed. In such service of the apparatus, the enclosed arrangement for the coil spring 14 as shown in Figs. 1 and 2, is especially advantageous, in shielding the spring from ice and salt, brine, moist, salty air, or other corrosive materials which are normally found in refrigerator cars. The tubes 15 and 16 may be filled with grease to assure further protection of the spring from corrosion and deterioration.

It will now be appreciated that the invention fulfills the objects stated above of retarding the downward movement of the hinged element, counterbalancing the weight as the element is increasingly affected by gravity during its downward movement, and of providing a means for retaining the hinged element in the vertical and horizontal positions. In addition, it will be noted that the device is of a particularly sturdy construction, and is well suited to severe and rigorous conditions. Furthermore, there is no need for any additional pivotal connection between the hinged members than the conventional pintle, so that, therefore, the construction of the device is essentially very simple and the exposed moving parts are a minimum in number.

It will also be appreciated that the counterbalanced hinge device of this invention is adaptable to many uses and can be made in various sizes depending on the nature of the application. It may be easily reproduced in relatively small size because of the simplicity of the parts. Furthermore, although the invention is primarily directed to the counterbalancing of a horizontally hinged element, it will now be seen that structures of the sort here shown and described may be adapted for use in other circumstances, as in hinged installations pivoted on other axes, wherein it is desired to retard the closing or opening of the hinged element or to limit or prevent its movement.

It is to be understood that the invention is not limited to the specific forms of the apparatus which have been described and illustrated but that the arrangements set forth have been merely illustrative. The invention may be carried out in other ways without departure from its spirit and scope.

What is claimed is:

A counterbalanced hinge structure for pivoting a movable member at one side on a horizontal axis to a stationary structure to provide for swinging said movable member between horizontal position and a vertical position above said horizontal position, comprising a first hinge element to be attached to the movable member, a second hinge element to be attached to the stationary structure, pivot means having a horizontal axis and pivotally connecting said elements for swinging said first element about said axis between said horizontal and vertical positions, a cam associated with said first element beneath the same and movable therewith about said axis and having a curved, downwardly facing cam surface eccentric to the axis, said cam being shaped so that the lowermost point occupied by said surface continuously and progressively falls as the first hinge element swings downward, said point being at its highest locality when the first hinge element is at its said vertical position and being at its lowest locality when the first hinge element is horizontal, said cam being arranged to transmit downward load of the first hinge element to the said lowermost point of the cam surface at all positions of said downward swing of the first hinge element, and resilient means carried by the second hinge element wholly below the first hinge element, said resilient means being at one end fixedly associated with the second hinge element and pressing flatwise upward at the other end against the cam surface at its lowermost point, said resilient means being compressible downwardly by the cam for resisting the downward load of the first hinge element progressively more and more as downward swing of the first hinge element progressively lowers said lowermost point of the cam surface, and said resilient means comprising a support rigidly carried by the second hinge element and disposed at a locality spaced vertically below the cam, a platform having a flat upper surface disposed beneath and in abutment with the cam surface at its lowermost point, a tubular sleeve extending rigidly upward from the support, a tubular sleeve extending rigidly downward from the platform, said sleeves being coaxial and one of said sleeves being disposed in vertically sliding, telescoping relation around the other of said sleeves, and a coil spring having a vertical axis and coaxially fitted within the inner one of said sleeves and fixedly seated under compression be-

tween the support and the platform, said telescoping sleeves cooperating to enclose the spring.
